ANTI-SLIP SHOE ATTACHMENT

Michael J. Hoffarth, Chicago Heights, Ill.

Application April 15, 1953, Serial No. 349,031

2 Claims. (Cl. 36—7.7)

This invention relates to shoe attachments and more particularly to anti-slip devices for detachable association with the regular walking shoes of individuals, although certain features thereof may be employed with equal advantage for other purposes.

It contemplates more especially the provision of an effective anti-slip device for detachable association with the shoe or overshoe such as galoshes and rubbers of the wearer in a manner that will more effectively approach the normal use of anti-slip devices when permanently attached to the soles of special shoes such as those worn by golfers or equipped with special pegs more effective for use in walking over icy pavements and streets. Numerous anti-slip devices both of the permanent and detachable type have heretofore been proposed, but these have not been proven entirely satisfactory in that they were either permanently or detachably associated with instrumentalities that did not effectively hold without binding, creeping, rendering the wearer uncomfortable, or being entirely effective as an anti-slip device. With the teachings of the present invention, anti-slip expedients such as pegs can be anchored to a shoe sole conforming flat member provided with instrumentalities that are effective for detachable association with the usual sole of shoes or to overshoes such as galoshes or rubber worn by individuals in all walks of life.

It is proposed to provide two different sizes for effective detachable association with shoes for men, and also two sizes for women so that shoes or overshoes of all classifications may be provided with devices embodying the teachings of the present invention. These limited number of sizes will be effective for detachable association to all footwear to insure walking with safety over icy pavements or streets. For that matter, the same style of devices could be utilized for playing golf should commercial practice so dictate. In the use of the device as an anti-slip attachment for icy pavements and streets, the pegs would be sharper and perhaps shorter than those normally used in playing golf, but with this exception the attachments are the same and could be interchangeably used. Preferably the two sets of special attachments could be provided so that one would be supplied with special pegs for icy pavements and the other with comparatively duller pegs for use in playing golf.

One object of the present invention is to simplify the construction and improve the operation of devices of the character mentioned.

Another object is to provide a more effective shoe attachment to use pegs as anti-slip devices for detachable association with the soles of ordinary shoes.

Still another object is to provide a detachable attachment for shoes which has an improved strap buckling arrangement that will not creep or bind during the act of walking.

A further object is to provide a shoe sole attachment having an improved heel vamp engaging structure in conjunction with improved holding straps that will effectively maintain a shoe sole conforming flat member in the desired engagement with the shoes of the wearer.

2

A still further object is to provide an attachment of the character mentioned for a shoe sole conforming flat member provided with laterally extending loops through which a holding strap is laced for connection with a heel vamp engaging loop to effectively retain its association with the shoe soles of the wearer.

Still a further object is to provide a shoe sole conforming flat member with a heel vamp engaging loop having separate pairs of complementary straps for lacing around the ankle of the wearer and peripherally around the shoe sole conforming flat member.

Other objects and advantages will appear from the following description of an illustrated embodiment of the present invention.

In the drawing:

Figure 1 is a side view in elevation of the device embodying features of the present invention and shows in its operative position in detachable association with the shoe of the wearer.

Figure 2 is a front view in elevation of the device shown in Figure 1.

Figure 3 is a bottom plan view of the devices shown in Figures 1 and 2.

Figure 4 is a top plan view of the anti-slip device in its detached and inoperative relationship relative to a shoe and preparatory to its application thereto with the straps shown unbuckled and unlaced.

Figure 5 is a top plan view similar to Figure 4 with the straps buckled and laced in a manner that would effectively retain it in association with a shoe of a wearer (not shown).

The structure selected for illustration is not intended to serve as a limitation upon the scope or teachings of the invention, but is merely illustrative thereof. There may be considerable variations and adaptations of all or part of the teachings depending upon the dictates of commercial practice.

The present embodiment comprises a substantially flat shoe sole conforming member 10 preferably though not essentially stamped or otherwise shaped from flexible leather or any other suitable composition material having a thickness sufficient for rigidity and the property of limited flexibility. As shown, the shoe sole conforming flat member 10 is provided with a plurality of laterally extending short straps 11—12, 13—14 and 15—16, in this instance six, although the number may vary depending upon the dictates of commercial practice. It should be noted that the oppositely disposed short straps 11—12 and 13—14 are disposed normally to the longitudinal median line of the shoe sole conforming flat member 10 while the rearwardly positioned short straps 15—16 are disposed at a small angle to more effectively serve their intended purpose. The short straps 11—12, 13—14 and 15—16 terminate in loops 17 formed from the material thereof by a fold-over which is sewed or preferably riveted at 18 to define the loops 17 substantially in the direction of the perimeter of the shoe sole conforming flat member 10 to receive a strap that is laced therethrough as will be described more fully hereinafter.

A heel vamp engaging strap loop 19 preferably of flexible leather or other suitable material is anchored to the edge 20 of the shoe sole conforming flat member 10 in the region of its joinder with the arch of the normal shoe, and this can be accomplished by sewing or preferably anchored with suitable fasteners such as a plurality of rivets 21, in this instance three. It may be desirable to reinforce the shoe sole conforming flat member 10 in its rearward region by applying another thickness of leather 22 thereunder and having this sewed and anchored around its substantially rectangular perimeter and utilizing the same fasteners or rivets 21 for that purpose which anchor the heel vamp engaging loop 19 thereto. Should com-

mercial practice so dictate, the substantially rectangular reinforcement 22 is not essential and may be dispensed with unless the attachments are made for heavy duty use such as in extreme conditions for use by the military and those who do a lot of walking such as policemen.

With the structure thus far described the intended wearer of the device could apply the sole of the normal shoe over the shoe sole conforming flat member 10 so that the heel of the normal shoe would pass through the loop 19 and the latter manually elevated to engage the convexly shaped heel vamp 22' of the normal shoe 23 (Figure 1). So that the shoe sole conforming flat member 10 would be held flat against the normal shoe sole 24, the heel vamp engaging loop 19 is provided with two separate pairs of complementary straps 25-26 and 27-28 which extend from the upper portion 29 of the heel vamp engaging loop 19 while the lower portion 30 thereof is anchored to the shoe sole conforming flat member 10 by means of the fasteners 21 as described supra.

The two separate pairs of complementary straps 25-26 and 27-28 diverge as they extend forwardly from the upper anchor portion 29 of the heel vamp engaging loop 19, and the upper pair of straps 25-26 are substantially wider than the lower pair 27-28 which are intended for lacing through the loops 17 of the short straps 11-12, 13-14 and 15-16. The complementary strap sections 25-27 that are positioned outwardly on each of the shoe sole conforming flat members 10 that are shaped for left and right shoe application, are provided with buckles 29'-30', respectively, that are anchored thereto in the usual manner by means of fasteners such as rivets 31-32.

The other strap sections 26-28 have extremities that extend through and are complementary to the buckles 29'-30'. To this end, the end regions of the strap sections 26-28 are provided with a linear series of apertures or holes 33-34 that serve as complements of the buckles 29'-30' to define adjustable loops 35 and 36. The adjustable loops 35-36 extend respectively around the forward portion of the ankle and the shoe upper and also along and spaced above the perimeter of the sole in a slightly superposed position by reason of being laced through the short strap loops 17, thereby effectively holding the shoe sole conforming flat member 10 against the underside of the normal shoe sole 24 and to permit walking without any binding, creeping, or change of position of the heel vamp engaging loop 19 or the adjustable ankle sole loops 35-36 respectively. It should be observed that the heel vamp engaging loop 19 is bifurcated at its sides to present the diverging strap loops 35-36, the former strap loop 35 to prevent the heel vamp engaging strap 19 from riding down and the latter strap loop 36 to prevent the heel vamp engaging strap 19 from creeping up.

Any suitable form of anti-slip expedients may be applied to the bottom of the shoe sole conforming flat member 10. In the present embodiment there is illustrated a plurality of comparatively short sharp pegs 37, in this instance seven, which project therefrom for anchored engagement therein by resort to any suitable anchoring expedients such as the split rivet shanks 38. Should commercial practice so dictate, the usual type of threaded projecting studs may be provided so that substitution of

longer or duller pegs could be readily made for use in golfing in that the sharp pointed pegs illustrated herein are more effective for ice surface gripping traction. It will be apparent, therefore, that a very effective and simple anti-slip shoe attachment has been provided that provides for substantially complete coverage of the normal sole and may be supplied in several standard sizes for practically universal application to the shoes of wearers having a wide variety of sizes.

While I have illustrated and described a preferred embodiment of this invention, it must be understood that the invention is capable of considerable variation and modification without departing from the spirit of the invention. I, therefore, do not wish to be limited to the precise details of construction set forth, but desire to avail myself of such variations and modifications as come within the scope of the appended claims.

I claim:

1. An ice gripping shoe traction device of the character described adapted for detachable association with a shoe, said device comprising a shoe sole conforming flat member, a plurality of short straps extending laterally from said flat member, loops formed on the ends of said short straps, a heel vamp engaging strap loop extending from said flat member for reception of the shoe heel vamp therein, complementary strap portions extending from said heel engaging strap loop to envelop the shoe upper and ankle, buckles on one of said strap portions to engage a linear series of holes in the other portion of said complementary strap portions, another set of complementary strap portions extending from said heel engaging strap loop below said first named complementary strap portions, a buckle on one of said last named strap portions to engage the other complementary strap portion after the latter is laced through said short strap loops to securely hold the shoe sole conforming flat member in detachable association with a shoe, and downwardly extending projections anchored in said shoe sole conforming flat member for traction gripping of the surface over which the wearer treads.

2. An ice gripping shoe traction device of the character described adapted for detachable association with a shoe, said device comprising a substantially full shoe sole conforming flat member, a plurality of short straps extending integrally from said flat member, loops formed on the ends of said short straps, a heel vamp engaging strap loop extending from said flat member, two sets of divergent complementary adjustable strap sections extending from said heel vamp engaging loop, one set of complementary adjustable straps enveloping the shoe upper and ankle and the other set of complementary adjustable straps being laced through said loops on said sole short straps, and downwardly projecting gripping pegs mounted in said shoe sole conforming flat member for traction gripping of the surface over which the wearer treads.
